UNITED STATES PATENT OFFICE

THOMAS J. McCORMICK AND ROBERT E. LINN, OF DETROIT, MICHIGAN; SAID LINN
ASSIGNOR TO SAID THOMAS J. McCORMICK

DESIGN FOR A TIRE COVER

Application filed September 23, 1931. Serial No. 41,195. Term of patent 14 years.

To all whom it may concern:

Be it known that THOMAS J. McCORMICK and ROBERT E. LINN, citizens of the United States, residing at the city of Detroit, county of Wayne, State of Michigan, have invented a certain new, original, and ornamental Design for a Tire Cover, of which the following is a specification, reference being had to the accompanying drawing, forming part thereof.

Fig. 1 is a side view of the cover.

Fig. 2 is a back view of the cover looking in the direction of the arrow 2 of Fig. 1.

Fig. 3 is a cross section as if on the line 3—3 of Fig. 2.

Fig. 4 is a perspective view of the cover.

The dominant features of the design are

the provision of bright metal moldings on the polished black cover, these moldings being annular with one of them around the center of the tread portion and the other around the inner peripheral edge of the front face portion. The cover as a whole is made of black polished metal, whereas the moldings are made of a chrome plate or nickel plate polished metal contrasting in color and appearance with the rest of the cover.

What we claim is:

The ornamental design for a tire cover, substantially as shown and described.

In testimony whereof, we sign this specification.

THOMAS J. McCORMICK.
ROBERT E. LINN.
